US0D1040418S

(12) **United States Design Patent** (10) **Patent No.:** **US D1,040,418 S**
(45) **Date of Patent:** **** Aug. 27, 2024**

(54) **LIGHTING FIXTURE**

(71) Applicant: **W Schonbek LLC**, Plattsburgh, NY (US)

(72) Inventor: **Molly E. McGee**, Tiverton, RI (US)

(73) Assignee: **W Schonbek LLC**, Plattsburgh, NY (US)

(**) Term: **15 Years**

(21) Appl. No.: **29/938,935**

(22) Filed: **Apr. 24, 2024**

Related U.S. Application Data

(63) Continuation of application No. 29/791,056, filed on Dec. 28, 2021, now Pat. No. Des. 1,026,280.

(57) **CLAIM**

The ornamental design for a lighting fixture, as shown and described.

DESCRIPTION

FIG. 1 is a front right perspective view from above of a lighting fixture according to the new design;

FIG. 2 is a rear left perspective view from below thereof;

FIG. 3 is a front elevational view thereof;

FIG. 4 is a left side elevational view thereof;

FIG. 5 is a right side elevational view thereof;

FIG. 6 is a rear elevational view thereof;

FIG. 7 is a top view thereof; and,

FIG. 8 is a bottom view thereof.

The broken lines in the drawings illustrate portions of the lighting fixture that form no part of the claimed design.

The long dash-short dash lines in the drawings represent a boundary of the claimed design and form no part of the claimed design.

1 Claim, 7 Drawing Sheets
